Alfred Wilkins Jr.

UNITED STATES PATENT OFFICE.

JOHN R. CLANCY, OF SYRACUSE, NEW YORK.

HOSE-CLAMP.

No. 919,127.

Specification of Letters Patent. Patented April 20, 1909.

Application filed October 20, 1906. Serial No. 339,805.

To all whom it may concern:

Be it known that I, JOHN R. CLANCY, a citizen of the United States, residing at Syracuse, in the county of Onondaga and State of New York, have invented new and useful Improvements in Hose-Clamps, of which the following is a specification.

My invention relates to improvements in hose-clamps, and consists in providing the 10 perforated end ears with reinforcing side flanges, without increasing the width or thickness of the ends of the blank from which the clamp is formed; also in giving a slight outward bend to the tip of the 15 tongue to avoid cutting or injuring the material of the hose.

In clamps as heretofore made, the tip of the tongue (provided to span the space between the ears and prevent pinching of the 20 hose) rested in contact with the hose, or was pressed against it, often cutting and abrading the rubber, or other softer material, of which the hose was made. Old clamps have also been provided with side 25 flanges, but they were made from special blanks having wider or heavier ends, which was troublesome and expensive, and in the finished clamp the ends were as wide as the middle, therefore heavy and clumsy.

30 My invention is fully shown in the drawing herewith, in which the reference numerals of the description indicate the corresponding parts in all the figures.

Figure 1 is an elevation of a hose-clamp. 35 Figs. 2 and 3 are elevations of Fig. 1 respectively from the left and the right. Fig. 4 is a plan of a clamp, before being bent up, with the flanges formed at one end and with the opposite end left unfinished. Figs. 5 40 and 6 illustrate a modified form of clamp in which the tongue is made as a separate piece.

My hose-clamp is formed from a blank 45 of steel, brass or other suitable metal of uniform width and thickness so that the blanks may be cut, without waste, from the usual commercial bars, or plates. The ears 1 are bent up substantially at a right angle to the body of the blank, and the side edges at the ends are bent in forming the reinforcing flanges 2 for said ears, so that the 50 tips are narrower than the body of the clamp, as illustrated. Said ends are thus very strong to resist the strain of the clamping bolt 3, and also are neat, and give a good 55 finish and lightness in appearance to the entire clamp. As shown in Fig. 3, the nut 4

fits between said flanges, which also afford a seat and a lock therefor, to prevent accidental loosening.

My clamp is formed with the slots 6 7, 60 which assist in gripping the hose, and have another and important function. The metal from one of the slots (6) is entirely cut away, but for the opposite slot (7) is not so cut away at end 8 but is bent back inwardly 65 in a loop 9, to form the tongue 10, which spans the space between the ends of the clamp, when it is applied to the hose. It will be understood that the tip 11 of said tongue, when forced against the softer hose 70 under the opposite side of the clamp, tends to cut, or bite, into the hose, which is an objection long recognized, and the subject of complaint by users, but not heretofore remedied in any way so far as I know. It will be 75 understood that in stamping these clamps in large quantities, often the tongues are sharp, or provided with a bur which increases this danger. I have overcome this disadvantage 80 by forming the tongue end with a slight outward bend or curve, so that the tip does not come in contact with the hose and cannot be forced against it. It will be evident that such a construction of tongue tip is not practical with a solid hose clamp, but only where 85 the slot 6, or corresponding opening, is made to receive such outwardly bent tip. This apparently slight change has proved very successful and of great importance in practice.

Figs. 5 and 6 show a modified form of a 90 clamp to which my invention may be applied. The tongue, or tongue-piece, is formed separately as shown in Fig. 6, with a perforated, flat lug 12 bent up at an angle, corresponding to the angle of the ears 13. 95 This tongue-piece is secured to the body of the clamp by the bolt 3, with the tongue extending inwardly through the slot on one side, to span the space between the clamp ends, and having its outwardly bent tip received in the opposite slot. 100

My invention is particularly adapted to be applied to sheet metal clamps, but I do not wish to limit myself thereto, nor to the form here shown.

Having thus described my invention, what I claim as new and desire to secure by Letters Patent, is:

1. As a new article of manufacture, a one-piece sheet metal hose clamp, having outwardly extending, substantially parallel end ears, perforated for the clamping bolt, longi-

2

tudinal slots on the opposite sides of the clamp middle and extending adjacent to the ears, an integral tongue bent back and inwardly to span the space between the ears, 5 said tongue having an outwardly curved tip adapted to lie in the opposite slot when the clamp is in position, and reinforcing side flanges for the ears and ends of the clamp on both sides, said flanges being arranged inwardly of the edges of the body of the clamp 10 to form narrow ends.

2. As a new article of manufacture, a sheet-metal hose clamp formed from a blank of uniform width and thickness, from end to 15 end, said clamp having perforated end ears outwardly bent and substantially parallel, and reinforcing side flanges for the ears, said flanges being bent inwardly from the side margin of the clamp, to form clamp ends 20 narrower than the body and to span the corner formed between the ears and the clamp body, substantially as described and shown.

3. A metal hose-clamp having outwardly

extending ears at the ends of the body, means to clamp the ears together, and a tongue 25 adapted to span the space between the ends of the body, said tongue having its end outwardly curved away from the hose.

4. A one-piece sheet metal hose-clamp having perforated ears at the ends of the 30 clamp body, outwardly extending and substantially parallel, a clamping bolt fitted to said ears and a nut fitted to said bolt, an integral tongue attached at one end to the body and adapted to span the space between the 35 body ends, said tongue having its free end outwardly bent away from the hose, and the clamp body having a free space to receive said bent end.

In testimony whereof I have signed my 40 name to this specification in the presence of two subscribing witnesses.

JOHN R. CLANCY.
